LOAD LIFTING CRADLE

Benjamin F. Fitch, Greenwich, Conn., assignor
to Motor Terminals Company, Wilmington,
Del., a corporation of Delaware

Application June 7, 1932, Serial No. 615,906

13 Claims. (Cl. 294—67)

This invention relates to apparatus for connecting a lifting mechanism to a demountable automobile body, which may be loaded with package freight. My invention provides a load-engaging means arranged to be connected with the body at four points, two on each side, and adapted to be suspended in a horizontal position by suitable depending raising mechanism, whereby the body may be well supported for lifting while maintained in its level position.

More particularly, the invention is designed to raise demountable bodies having supporting hooks adjacent their eaves, and to that end provides a cradle or floating frame having shackles or loops pivotally mounted on the frame so that they may swing beneath the hooks.

My invention provides means employing fluid pressure transmission readily operable from a single point for moving shackles as a unit so that when the cradle has been lowered and guided into proper position relative to the hooks, an immediate engagement may be made, one of the objects of the invention being to provide a simple, certain and quickly operable means for effecting engagement.

Another object of the invention is to enable the cradle to engage bodies of different lengths, and this is accomplished by a ready adjustment of the position of the guides and shackles for different size bodies without interfering with the ready operation of the shackles.

Another feature of the invention relates to means for attaching the cradle to a single supporting hook of a suitable crane. This comprises a system of diagonal, articulated links connected to the cradle adjacent the shackles and terminating in loops adapted to be mounted on the hoist hook, together with a platform on the cradle adapted to support an operator who may conveniently place the loops on the hook. This platform serves also to sustain the articulated links when the cradle is unattached.

My invention, comprising the means by which I accomplish the above results, or any of them, is illustrated in the drawings hereof and is hereinafter more fully described.

In the drawings:

Fig. 1 is a side elevation of my cradle in position ready to be lowered for attachment to a body, the idle position of the articulated links being indicated in broken lines.

Fig. 2 is a side elevation of the cradle attached to be a demountable automobile body.

Fig. 3 is a plan of the cradle with the articulated links in idle position resting on a platform.

Fig. 4 is a vertical section through the shackle-operating mechanism, as indicated by the line 4—4 on Fig. 3.

Fig. 5 is a detail of the cradle frame and platform, being a section on the line 5—5 on Fig. 3.

Fig. 6 is a sectional elevation of a portion of the cradle showing the shackle-operating mechanism, the plane of the section being indicated by the lines 6—6 on Fig. 3.

Fig. 7 is a substantially horizontal section of the cylinder and plunger operating the shackle, as indicated by the line 7—7 on Fig. 6.

Fig. 8 is a side elevation of a portion of my cradle in a modified form arranged so that the position of the shackles and guides may be adjusted longitudinally.

Fig. 9 is a vertical section on the line 9—9 in Fig. 8.

Fig. 10 is a plan of another modification of the cradle, showing means for simultaneously adjusting the position of the four shackles and guides.

The remaining figures are in the nature of diagrams illustrating the use of the cradle, Fig. 11 showing it as attached to a demountable body on a flat car, but with the supporting links folded; Fig. 12 shows a portion of such equipment with the links in the position as first engaged to the raising hook; Fig. 13 illustrating the cradle and body after the latter has been raised from the flat car, and Fig. 14 as it is being deposited on a support.

Referring first to Figs. 2 and 11 to 14, inclusive, A indicates a demountable automobile body which may rest on a flat car B, or on a truck frame indicated conventionally at C in Fig. 14. This body A is indicated as of such size that two bodies may be readily mounted on an ordinary flat car or one body on a suitable truck. The body is provided with suitable floor frame, side walls, end walls and a roof and doors, side doors being indicated a. Each side of the demountable body is provided with two upwardly extending straps a¹, terminating in hooks a². These hooks lie substantially in the side plane of the container, and are located a short distance above the eaves of the container and face in opposite directions, preferably toward the ends of the container.

The cradle provides a floating rigid frame and suitable shackles pivotally carried thereby and adapted to coact with the hooks on the body above referred to. The frame may readily be a pair of longitudinal tubular side bars 10 and a pair of tubular end bars 11, joined to form a rectangle. The side bars are braced by cross bars 12 (Fig. 3) and at the corners there are preferably 55

triangular gussets 13. All of these parts may be readily connected by welding. Resting on the cross bars is a plate 14, further rigidifying the cradle and forming a platform adapted to support an operator, when desired.

At each corner of the frame, I have shown diagonal plates 20 resting on the side bars and end bars and secured to both of them by welding. Extending through these plates and through the 10 two bars are inverted U-shaped bolts 21, which are shown as having nuts on their under sides. On the under side of the cross bars is a member 22 recessed to engage the hooks a^2 to guide the cradle into position. These guides have longitudinally extending portions 23 adapted to engage the inner face of the hook, and lateral portions 24 (shown in dotted lines on Fig. 6) to engage the back of the hook, so that the hook operates to cam the guide lengthwise or sidewise, as 20 the case may be, to position the cradle definitely, as it comes to rest on the hooks.

The member 22 may have a flange at its upper end resting against the under sides of the bars, and the bolts 21 may pass through such flange. 25 I prefer to weld the flange to the under sides of the frame bars; also, to weld the bolts and nuts to the flange after the parts are assembled. This makes a very rigid and firm anchorage for the upwardly extending loops to which the supporting and raising devices are secured.

The supporting connection to the loops comprises four articulated hog rods, each consisting of a lower member 30 having an eye 31 passing through the loop 21 and an upper member 32 connected with the member 30 by interlocking eyes 33 on the two members and connected at its upper end by eyes to a ring 35. There are two of these rings 35, each of which serves for the two hog rods on that side of the cradle.

40 When the cradle is idle, the articulated hog rods, with their common terminal rings 35, lie in horizontal position on the platform 14 substantially as shown in Fig. 3 and in dotted lines on Fig. 1. When the cradle is to be attached to a 45 lifting hook, the cradle operator mounts the platform, and the crane operator lowers the hook until it is in convenient position for the cradle operator standing on the platform. The cradle operator then picks up one of the rings 35 and 50 raises the two upper sections of the jointed hog rods 32 and hooks them onto the crane hook. Such crane hook is illustrated at D in the diagrams and in Fig. 1. The position of the hog rods, as they are being attached to the hook, is 55 shown in Fig. 12.

The size of the demountable body is preferably as large as can be conveniently carried on a truck, or two of them on a flat car, and the length of the cradle is conveniently about three-fourths of 60 that of the body, so as to enable it to carry shackles coacting with hooks set in the desired distance from the end of the body. This dimension requires the diagonal tension members leading to the single hoist hook to be of considerable 65 length to give them a sufficient vertical component in use and prevent an undue buckling strain on the cradle, and then the cradle is supported by the single hook, such hook is a greater distance above the cradle than can be conveniently 70 reached by a man standing on the cradle. However, by means of the articulated links, when the upper members thereof are in position shown in Fig. 12, the hoist hook is approximately breast high for a man standing on the platform, so 75 that he can very readily mount the ring 35 on

the hoist hook while the upper links are resting at their lower ends on the platform. Accordingly, though the articulated links have considerable weight, in order to provide the necessary strength, the construction enables one man to connect the cradle to the hook easily and speedily.

It will be noticed that when the articulated hog rods are lying on the platform, as shown in Fig. 3, they are out of the way and, if desired, the cradle 10 may be transported on top of the container on a car or truck.

The supporting shackles 40 are pivotally carried by the side bars of the cradle at the fittings 20, these shackles being U-shaped members having eyes 41 at their upper ends embracing pins 42 extending horizontally through the fittings 20 and the embraced cradle bar 10, these pins being shown as held in position by cotter pins 43. This makes a very direct connection between the 20 shackles and the articulated hog rods, so that the lifting stresses are directly transmitted from the body to the lifting rods.

To operate the various shackles 40 simultaneously from a single point, I provide the hydraulic mechanism illustrated particularly in Figs. 3 to 7, and which comprises essentially a cylinder and piston operated by a single manual lever, piping transmitting the fluid under pressure from such cylinder and piston to individual cylinders and pistons located at respective shackles and connected therewith. This construction will now be described.

Mounted on a suitable plate 16 on the cradle frame is a housing 50 carrying an oil chamber 51 and a cylinder 52 in communication with the oil chamber through a port 53. The oil chamber 51 may be supplied from time to time, if necessary, through the plug 58, which acts also as a vent for the chamber. On the end of the cylinder 40 52 is mounted a bonnet 54 from which several conduits 55 lead to the different shackle-operating cylinders. Within the cylinder 52 is a plunger 60 normally held behind the port 53 by an internal compression spring 61. This spring bears 45 against a disc 62 resting against the inner face of the bonnet. There are passageways 63 through the disc normally closed by the head 64 of a check valve under the influence of a spring 65.

Now, if the plunger 60 is moved inwardly in 50 the cylinder 52, this puts under pressure oil in the cylinder which came from the oil chamber through the openings 53, and will thus force oil under pressure through the conduits 55 to operate the shackle plungers. To move the plunger 55 60, I have provided a suitable manual lever 70 secured to a rock shaft 71, which is journalled in the housing 50, and on this rock shaft, within the housing, is a bent arm 72 resting against the outer end of the plunger 50. Accordingly, if the lever 70 is drawn down, the arm 72 will shove the plunger inwardly.

The shackle operating mechanism is illustrated in Figs. 6 and 7. I have there shown a bracket 65 80 depending from the cradle gusset plate 13. Pivotally connected to this bracket is a tubular fitting 81 with which communicates one of the pipes 55. The internal space 82 in this fitting constitutes a cylinder in which a piston 84 operates, this piston being connected with the shackle 42. Preferably, the member which is attached to the shackle is a rod 85 bifurcated at one end to embrace the shackle and having a reduced portion 86, which is slidable within the plunger 84, 75

a suitable collar 87 on the rod resting against the end of the plunger.

The inner end of the plunger 84 may carry a rubber disc, or other packing 89, making a tight connection with the cylinder wall. A tubular telescoping member 88 embracing the end of the cylinder 84 and also embracing the rod 85 provides a dust protection.

It results from the construction described that the hydraulic pressure transmitted through the pipe 55 acting on the plungers 84 will shove them ahead and thus swing the shackles 43 into diagonal position, as illustrated in Fig. 1, where they will clear the hooks. The action, however, is only in one direction, and the construction does not prevent the shackle being swung into this position manually or otherwise, as this is allowed by sliding connection of the rod 85 and the bushing plunger 84, the rod simply withdrawing to some extent from the plunger.

The various shackles are provided with suitable means tending to bring them into vertical position. This means may comprise counterweights 45 on the ends of rods 46 forming a rigid part of the shackle and extending above its pivot and then longitudinally as illustrated in various figures.

As a convenient means for operating the manual lever 70, I provide a hand rope 75 secured to the lever and depending at the side of the cradle. This hand rope is formed with a knot 76 a slight distance below the lever, and this knot is adapted to be engaged beneath a keeper 77 in the form of a hook lying in a horizontal plane and secured to adjacent longitudinal bar 10 of the cradle.

With the shackle operating mechanism described, if the operator pulls down on the rope 75, he puts the oil in the cylinder 52 under pressure, which then puts under pressure oil in the various pipes 55 leading to the four shackle cylinders and plungers, and this operates each plunger 84 to swing the four shackles into idle position, raising their counterweights as shown in Fig. 1. If desired, the shackles may be retained in this position by merely hooking the rope 75 behind the keeper 77, the knot 76 preventing the rising of the lever 70.

With the shackles retained in the idle position, either by the locked rope or by the operator maintaining a tension on the rope, the cradle is lowered onto the body, being guided accurately by the guides 22, so that the shackles stand in front of the space below the hook points, as shown in Fig. 14. Then the operator releases the rope 75, releasing the pressure in the cylinder 52 and in the pipes 55, and immediately the counterweights 45 swing the shackles into vertical position where they stand within the opening of the hooks a², as shown in Fig. 6. Now as soon as the hoist lifts the cradle, the shackles come into engagement with the hooks, as shown in Figs. 2 and 13, and may thus lift the body.

To enable quick action of the shackles in entering the hooks under the influence of the counterweights, the valve construction shown in Fig. 4 in the hydraulic actuator is employed. It will be seen that the check valve 64 seats against the movable disk 62, which is normally held against the face of the bonnet 64 by the spring 61. As soon as the actuating pressure on the plunger 60 ceases, the check valve 64 seats and the pressure is retained in the pipes 55; but when the actuating force is released on the lever 70, the spring 61 reacting forces the plunger 60 to idle position and thus the spring loses its force and the disk 62

ceases to be maintained tightly on its seat, and hence the superior pressure beyond the check valve may force back the check valve head and the disk, the oil escaping around the edge of the disk into the cylinder 52. This results in a quick release of the shackles.

To support the conduits 55 conveniently, and prevent injury thereto, I provide protecting piping which forms a permanent part of the cradle, and in which the conduits may be readily mounted. Such protective piping is shown in Figs. 3 and 5 at 90 adjacent one of the side bars 10, and at 91 and 92 adjacent the two end bars 11.

To enable convenient adjustment of the shackles for different lengths of automobile bodies, I may mount the shackles on the fittings rather than on the side bars, and make the fittings slideable on the side bars. Such construction is illustrated in Figs. 8 and 9. In these figures, the fitting 120, to which the lower member 38 of the articulated hog rod is secured by the loop 121, is slideable on the side rod 10, being held in selected position thereon by a pin 109 occupying any of a number of holes 101 in the side bar. When this construction is employed, the shackle pin 42 extends through a bar 125 on the fitting, and the cylinder 82, instead of being pivoted to a cradle bracket 80 as heretofore is now pivoted to an ear 126 on the fitting, and the conduit 55 leading to the cylinder 82 is flexible.

The construction just described enables the shackle and its operating mechanism to be all self-contained on the fitting 120, which is adjustable on the cradle. This is a valuable feature when it is desired to use the cradle for bodies of different lengths.

In place of adjusting each fitting 120 manually and locking it by the pin 109, I may employ the construction of Fig. 10, where each fitting 220, carrying the shackle and operating mechanism, has rigid with it a nut 227 engaged by an operating screw. I have shown four of these screws 210 leading from the respective fitting nuts along the inner face of the cradle bars 10 and terminating in beveled gears 211, adjacent beveled gears 212 meshing with gears 213 on a cross rod 214 which carries an operating crank 214. By rotating this crank, the four screws are turned simultaneously, and these screws are equipped with right or left-hand threads, as may be required to cause a simultaneous action in the same direction of the two shackles adjacent the same end of the cradle, this direction being opposite that of the two shackles at the other end. Accordingly, the rotation of the crank in one direction will spread the four shackles, and the opposite rotation draw them toward each other.

I claim:

1. The combination of a rectangular frame adapted to be suspended, four fittings slidably mounted thereon, two on each side, load engaging shackles pivoted to the respective fittings, individual pistons and cylinders carried by the fittings and shackles to operate the latter, a master actuator on the frame, and conduits leading therefrom to the individual pistons and cylinders.

2. In a load lifting device, the combination of a frame adapted to be suspended, four fittings movably mounted thereon adjacent the four corners of a rectangle, four shackles pivotally mounted on the respective fittings, four individual operating devices mounted on the fittings and coacting with the shackles, fluid pressure transmission mechanism leading from a single actuator to said four operating devices, and means

for holding the four fittings in different positions on the frame.

3. The combination of a rigid horizontal open rectangular frame adapted to be suspended, four fittings slidably mounted thereon, shackles pivot-
5 ed to the respective fittings, means for simultaneously moving the two fittings on each side toward each other or from each other and means for simultaneously operating the four shackles.

10 4. The combination of a suspended horizontal frame, four shackles pivoted thereto at four corners of a rectangle and adapted to engage correspondingly located members on a demountable body, four fluid pressure mechanisms for operating the four shackles respectively, a device on the frame for manually causing fluid pressure, and means for conducting such pressure to the individual mechanisms.

15 5. In a load lifting device, the combination of a suspensible frame, four depending shackles carried thereby, two on each side, a guide associated with each shackle and adapted to coact with hooks on a demountable body to guide the frame into position where the shackles are adjacent the mouths of the hooks, four fluid motors connected to the respective shackles, and a conduit leading from a common actuator on the frame to the four motors, whereby they may be operated as a unit.

20 30 6. The combination of a suspended frame, four shackles pivoted thereto and adapted to engage two pairs of hooks located respectively on opposite sides of a demountable body, counterweights on said shackles tending to move them in one direction, four operating devices for swinging said shackles against the action of the counterweights, a master actuator on the frame for actuating the operating devices, and a cable operatively connected therewith and depending at the side of the frame and accessible at the side of the demountable body engaged by the shackles.

25 40 45 7. The combination of a rectangular frame adapted to be suspended, four shackles pivotally carried thereby adjacent the four corners of the frame, individual cylinders carried by the frame adjacent the shackles, pistons in the individual cylinders connected to the shackles respectively, a master cylinder carried by the frame, conduits leading from the master cylinder to the individual cylinders, mechanism adapted to operate the piston of the master cylinder, said mechanism having a lever adjacent one side of the frame, a cable depending from said lever and adapted to move the lever to operate the piston of the master cylinder, and means adapted to return the lever.

50 55 60 8. The combination of a frame adapted to be suspended, depending shackles pivotally carried thereby, and positioned to engage spaced attaching devices on a demountable body to be lifted, an oil chamber carried by the frame, a master

cylinder normally in communication with the oil chamber, a piston in the master cylinder adapted to shut off such communication and put the oil in the master cylinder under pressure, individual cylinders carried by the frame adjacent the shackles, pistons in the individual cylinders connected to the shackles respectively, conduits leading from the master cylinder to the individual cylinders, and mechanism adapted to operate the piston of the master cylinder.

10 15 20 9. The combination of a horizontal rectangular frame, means for suspending it, four load engaging members pivotally carried by the frame, two on each side, individual fluid pressure means for operating the load engaging members, a master fluid pressure actuator carried by the frame, protecting pipes rigidly carried by the frame, and conduits leading from the actuator to the individual fluid pressure means, said conduits being externally smaller than the bore of the pipes and located within said pipes.

25 10. The combination of a frame, comprising two spaced side bars and cross bars each rigidly connected to both side bars, fittings thereon adapted to be located in various positions, shackles pivotally mounted on the fittings, operating devices therefor carried by the fittings, and a common actuator for the different operating devices.

30 11. The combination of a rectangular frame, load engaging shackles pivotally carried thereby, a platform on the frame, and articulated hog rods connected to the corners of the frame and adapted to lie idly on the platform or be attached to a hoist hook, the upper members of the hog rods having a length such that when held substantially upright with their lower ends resting on the platform, their upper ends will be at least as high as the waist of a man standing on the platform.

35 40 45 12. The combination of a frame adapted to be suspended, load-engaging shackles carried thereby, fluid pressure transmission mechanism for operating the shackles simultaneously from a single point, comprising a master pressure device and individual piston-and-cylinder couples in communication therewith, there being one couple for each shackle, and devices movably mounted on the frame and each supporting one shackle and its corresponding couple, whereby the location of the shackles on the frame may be changed without interfering with their fluid operating mechanism.

50 55 60 13. The combination of a rectangular frame adapted to be suspended, four fittings slidably mounted thereon, two on each side, load engaging shackles pivoted to the respective fittings, individual shackle-operating devices carried by the respective fittings, and a master actuator adapted to supply power simultaneously to said operating devices irrespective of the setting of the fittings.

BENJAMIN F. FITCH. 60
